Primary Examiner — Elizabeth J Oswecki(74) *Attorney, Agent, or Firm* — Nutter McCennen & Fish LLP(57) **CLAIM**

The ornamental design for a shoe buckle, as shown and described.

DESCRIPTION

FIG. 1 is a front perspective view of a shoe buckle showing my new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a front view thereof, shown in a used condition on a shoe shown in broken lines.

The broken lines shown in the drawings represent portions of the shoe buckle, that form no part of the claimed design.

1 Claim, 6 Drawing Sheets(56)
